FIG.6.

UNITED STATES PATENT OFFICE.

FRITZ TITTELBACH, OF NEUODERNITZ, NEAR NIESKY, GERMANY, ASSIGNOR TO
CHRISTOPH & UNMACK ACTIEN-GESELLSCHAFT, OF NIESKY, GERMANY.

RAIL VEHICLE.

Application filed September 16, 1927, Serial No. 219,830, and in Germany September 29, 1926.

Experience in railway operation has shown that in case of derailments or collisions of trains, the usual construction of the railway carriages, especially of the so-called corridor-carriages, is not of sufficient rigidity in longitudinal direction, and in consequence of this in case of derailments or collisions a "telescoping" of the carriages will frequently take place.

10 This invention is designed to provide a re-inforced construction for rail vehicles in general and for railway carriages in particular, whereby the aforementioned drawback of insufficient rigidity of the carriages in longitudinal direction will be most effectively avoided. According to this invention the railway carriage or other rail-vehicle is provided with a body frame or skeleton which forms a closed structure composed of 20 a plurality of adjacent cells. The body frame or skeleton according to my invention is formed by two under and upper girders which are connected with each other by means of special connecting or re-inforcing 25 members, such as for instance vertical pillars and horizontal transoms which are properly connected with said girders so as to resist bending strains as much as possible. This body frame or skeleton forms a unitary 30 structure extending between the rear and front wall of the railway carriage in such a manner that the under girders are positioned within the under frame and the upper girders within the roof of the carriage.

35 The above-mentioned body frame or skeleton, therefore, provides two longitudinally extending girders of specific construction which are competent to impart to the carriage a far greater resistivity against strains 40 imposed therein in longitudinal direction, that is against the impacts which are due to collisions or the like, than had heretofore been possible by the usual construction with longitudinal girders provided solely in the 45 under frame of the carriage. In contradistinction to the known constructions of railway carriages, the outer wall of a carriage which is constructed according to this invention serves only to a very limited extent 50 as a support, and the strains which are imposed upon the carriage in case of derailments, collisions or the like will be essentially taken up by the afore-mentioned body frame or skeleton. The supporting members for the lateral walls according to this

invention project laterally from the said body frame or skeleton.

The upper and the under girder may be constructed in any desired manner, and may consist, for instance, of profiled iron or it 60 may be constructed as a plate-girder or as a frame-work girder. The upper girders may be positioned within the clear story, or if such is not present within the outer roof and an especially provided inner roof.

65 In case of corridor-carriages having the corridor provided at the side of the carriage the re-inforcing frame work body for the carriage may be so arranged that the one supporting wall will be positioned in the 70 plane of the interior lateral wall of the corridor and the other supporting wall may then be arranged symmetrically thereto. The connecting members are positioned within the partition walls which form the 75 several compartments of the carriage. These connecting members may thereby be formed as independent columns or they may consist of plate girders from which door-sashes or the like may be cut out.

80 In case of carriages of especial construction such as for instance hospital or ambulance carriages a still increased safety may be provided by the arrangement of a protective cell at the rear and front end of the 85 carriage. These protective cells are thereby formed by a wall of sheet metal which is provided intermediate the corners and two intermediate longitudinal frames which serve as a re-inforcement against the pillars 90 for the rear and front wall and the under girders of the body frame or skeleton.

95 The drawing shows several constructional forms of a frame body or skeleton for railway carriages according to my invention. Fig. 1 is a diagrammatic perspective view of a frame body or skeleton according to my invention, Fig. 2 an arrangement similar to Fig. 1 in connection with two protective cells, Fig. 3 a longitudinal section through 100 a carriage constructed according to my invention, Fig. 4 the plan view appertaining to Fig. 3, Fig. 5 a cross-section taken on Fig. 3 and Fig. 6 a similar cross-section showing a detail of a modified construction. 105

The body frame consists of two under girders α and α_1 which pass all over the railway carriage in longitudinal direction thereof as for instance shown in Fig. 5.

110 The under girders are connected on the

one hand with vertical pillars b and b_1 , which may for instance consist of channel-iron. These pillars are so distributed that they are positioned within the walls intermediate the several compartments of the carriage as shown in Fig. 4. The upper ends of the pillars b and b_1 are connected to the upper girders c and c_1 , which in connection with the construction shown in Fig. 5 serve simultaneously for forming the clear story of the carriage.

The upper girders likewise pass all over the length of the carriage and are downwardly bent in the usual manner near the front and rear wall of the carriage. At this place the upper girders are connected to the front and rear pillars d and d_1 , which may, for instance, be made of an iron bar having Z-shaped cross-section, in order to provide an especially solid connection. These pillars of Z-shaped cross-section may be used at the same time as a connecting member for the gangway-bellows.

The carriage, as seen in plan-view, is of the usual form tapering towards the ends, as shown in Fig. 4, the middle part of the carriage being of rectangular form. According to Fig. 2 especial re-inforcing walls e are provided at the rear and front parts of the carriage in order to form special protective cells at the rear and front ends of the carriage near the rear and front walls of the rectangular part of the carriage. These reinforcing walls which may be provided with door-sashes or the like serve to augment the rigidity of the carriage at these places. The walls e serve simultaneously for the connection of further intermediate longitudinal frames f and f_1 which extend from the walls e towards the front and rear ends of the carriage. The walls e therefore will provide at these places an additional re-inforcement, which is especially well adapted to protect the carriage against destruction in case of collisions.

Fig. 1 shows at one end of the carriage the usual double-buffer system and at the other end a single buffer together with the mode of connection for either of these buffer constructions with the body frame or skeleton of the carriage. The construction of the body frame or skeleton of the carriage according to this invention, as represented in Fig. 1, is therefore well adapted for either system of buffers.

As above mentioned, Figs. 3 to 5 show a carriage with a clear story. In Fig. 6 a modified construction is shown which comprises a double roof such as is frequently

used in railway carriages. In this case the upper girders c and c_1 are positioned intermediate the outer roof g and the interior roof h .

I claim:

1. A rail vehicle comprising a frame body forming a closed structure composed of a plurality of adjacent cells, said frame body including an under girder positioned in the under frame of said vehicle, an upper girder arranged in the roof of the vehicle, and perpendicular connecting members between said under and upper girders, the width of said frame body being smaller than the width of the vehicle so that the sides of the frame are positioned inwardly a certain distance apart from the outer walls of the vehicle.

2. A corridor carriage for railways, comprising a frame body forming a closed structure and consisting of a plurality of cells adjacent to each other in longitudinal direction of the carriage; an under girder and an upper girder, both forming part of said frame body and being positioned in the under frame and in the roof of said carriage, respectively; vertical pillars forming part of said frame body and positioned intermediate said under and said upper girder; said under girder, said upper girder and said pillars being positioned in the plane of the interior corridor wall of said carriage; and transoms intermediate the points of union of said girders with said pillars.

3. A corridor carriage for railways, as specified by claim 2, wherein an additional system of an under and upper girder and vertical pillars is arranged at a plane which is positioned symmetrically to the other system which comprises an under and upper girder, pillars and transoms.

4. A railway carriage as specified by claim 1, wherein the upper girder is positioned within the clear story of the carriage.

5. A railway carriage as specified by claim 1, having a double roof, and upper girders positioned between the under and upper part of said double roof.

6. A railway carriage, as specified by claim 1, having a re-inforcing cell provided at either end of the carriage, said re-inforcing cells including a wall of sheet metal extending transversely through the carriage and a pair of additional frames positioned within said cells in longitudinal direction of the carriage.

In testimony whereof I have hereunto affixed my signature.

FRITZ TITTELBACH.
